UNITED STATES PATENT OFFICE

165,316

FINGER RING

Grace A. Youmans, Greenwich, Conn.

Application July 9, 1951, Serial No. 15,786

Term of patent 7 years

(Cl. D45—10)

To all whom it may concern:

Be it known that I, Grace A. Youmans, a citizen of the United States of America, residing at Greenwich, Connecticut, have invented a new, original, and ornamental Design for Finger Rings, of which the following is a specification, reference being had to the accompanying drawings, forming a part hereof, and wherein:

Fig. 1 is a face view of a finger ring, showing my new design; and

Fig. 2 is an elevation of the same.

I claim:

The ornamental design for a finger ring, substantially as shown.

GRACE A. YOUNMANS.
